 Lovell Manufacturing Company, Erie, Pa., a
 corporation of Pennsylvania

Application August 8, 1947, Serial No. 767,615

14 Claims. (Cl. 68—255)

1

This invention is a clothes wringer, features of which include a safety release and an index actuated by a thrust on the wringer. Other objects are features increasing the sensitivity of the release and preventing unwanted operation of the release and index. Further objects and advantages appear in the specification and claims.

In the drawings, Fig. 1 is a side elevation of a wringer in section through the wringer head; Figs. 2 and 3 are fragmentary views of the reversing roll drive gears and of the shifter arm; Fig. 4 is a section of line 4—4 of Fig. 2; Fig. 5 is a fragmentary section through the roll end of the roll drive coupling; Fig. 6 is a section of an alternative roll drive coupling; Fig. 7 is an end view of the lubricating arrangement for the roll drive gear; Fig. 8 is a bottom view of the wringer head casting; Fig. 9 is an end view of the wringer head showing the driving gearing latched in the driving position; Fig. 10 is a view similar to Fig. 9 showing the position of the parts upon release of the driving gearing; Fig. 11 is a fragmentary view showing the position of the blocking plate for the index lock upon return of the wringer to a central position following release of the driving gear; Fig. 12 is a perspective view of the blocking plate for the index lock and Fig. 13 is a back view of the latch plate for the drive gearing.

Referring to the drawing, 1 indicates the wringer head, 2 the bottom frame, 3 top frame, 4 and 5 the upper and lower rolls, and 6 the water boards carried by the bottom frame. One end of the top frame is hinged at 7 on a bracket 8 projecting from the bottom frame over the top of the wringer head and the other end of the top frame is connected to the bottom frame through a toggle release lever 9. The roll pressure spring (not shown) is arranged between the top and bottom frames. A roll pressure release bar 10 actuates roll pressure release mechanism (not shown) releasing the pressure between the rolls. The parts so far described are or may be of common construction.

The wringer is pivotally mounted on the head by a shoulder bolt 11 extending through the bracket 8 and by a shoulder bolt 12 extending through a bracket 13 at the lower end of the bottom frame 2. The pivot axis of the frame extends substantially through the roll end of a roll drive coupling 14 as shown in detail in Figs. 5 and 6. The roll drive coupling comprises a tubular sleeve slotted at each end to receive tangs 15 respectively on a roll drive shaft 16 and on a shaft 17 cast in the hub 18 of a crown gear 19.

As shown in Fig. 5, the slotted ends of the coupling have rounded drive faces 20 which accommodate variations in angular alignment of the shafts 16 and 17. The pivot axis of the wringer frame extends substantially through the normal point of driving contact between the tang 15 on the roll drive shaft and the curved driving faces 20. This means that the driving torque exerts substantially no turning moment tending to pivot the frame about its mounting 11, 12. The same result is achieved with the form of drive coupling shown in Fig. 6 which comprises a tubular sleeve 21 having a slotted end 22 receiving a drive pin 23 in the roll drive shaft 16.

15 The hub 18 of the crown gear 19 is journalled in a porous metal bearing 24 pressed in a boss 25 on the wringer head casting. Around the outer periphery of the bearing are grease receiving grooves 26. The back face of the crown gear 20 wipes across eccentric grease feeding grooves 27, the inner ends of which are tangent to the upper and lower grooves 26. In either direction or rotation, grease will tend to be fed from the grooves 27 into the ends of the grooves 26, thus assuring 25 replenishment of the lubricant for the bearing 24. The crown gear meshes continuously with upper and lower drive pinions 28 and 29 loose on a shaft 30 having a slotted lower end 31 for connection with a drive shaft (not shown) extending up through the wringer post 32. Splined on the upper end of the shaft 30 is a clutch collar 33 having a groove 34 receiving a shifter bar 35. The bar is shifted up and down on the shaft 30 by a pin 36 in an eccentric 37. In the driving position illustrated in Fig. 2, the pin 36 is at one side of the shaft 30 so that the separating force caused by engagement of tapered teeth 38 on the clutch and drive pinion would normally tend to 35 tilt the shifter bar 35 about the pin 36 and thereby produce excessive pressures on the upper and lower surfaces on the groove 34. This pivoting is resisted by projections 39 on the end cover plate 40 of the wringer head. This means that in the driving position the shifter bar 35 is held essentially horizontal or parallel with the side walls or end walls of the groove 34. The construction is such that close tolerances are not required because even if the projections 39 permit the shifter bar to assume a position slightly away from the horizontal the movement from the horizontal is limited so as to prevent excessive wear. In the neutral position shown in Fig. 3 the shifter bar is out of contact with the projections 39 but in this position there is no separating force on 40 50 the clutch teeth tending to tilt the shifter bar.

The angle of the tapered driving teeth 38 is chosen so that under all conditions the driving torque tends to positively move the clutch toward the neutral position. This prevents jamming engagement of the teeth which might prevent breaking the driving connection under stalled or heavy load conditions.

The clutch is controlled through a shaft 41 journalled in the cover plate 40 of the wringer head and having its inner end fixed to the eccentric 37 and its outer end fixed to a latch plate 42. The latch plate has a pin and slot connection 43 with a cam plate 44 fixed to a hub 45 journalled on a reduced portion 46 of the shaft 41. On the outer end of the hub 45 is fixed a control handle 47. Endwise movement of the hub 45 is prevented by a set screw 48 having its inner end received in a groove 49. The latch plate 42 is held in the driving position by a pin 50 carried by one arm of a bell crank latch lever 51 pivoted at 52 on the end plate 40. In the driving positions the pin 50 engages either a surface 53 or a surface 54 on the latch plate 42. The angularity of the surfaces 53 and 54 being such that in the driving positions the force exerted on the pin 50 tends to move the pin inward along the surfaces 53 or 54. While from Fig. 13 it would appear that the angularity of the surfaces 53 and 54 is different, in the driving position the angularity with reference to the pin 50 is the same. The latch pin 50 is biased toward the surfaces 53 and 54 by a spring 55 arranged between an ear 56 on the lever 51 and a pin 57 on a bell crank lever 58 pivoted at 59 on the cover plate 40. Associated with the bell crank lever 58 is another bell crank lever 58a pivoted at 52 on the cover plate. The bell crank levers 58 and 58a have arms 59, 59a presented toward each other and connected by a tongue and slot connection 60 so that the bell crank levers 58 and 58a pivot together and in opposite directions about their respective pivots 59 and 52. The tension of the spring 55 urges the bell crank levers 58 and 58a against the outer faces of walls 61, 61a depending from the bracket 8. The spring 55, therefore, tends to center the wringer frame with respect to the wringer head. When the parts are in the driving position illustrated in Fig. 9, a push or pull on any part of the wringer overhanging the wringer head causes the wringer frame to pivot about the bolts 11, 12 and thereby move the bracket 8 to one side of a center position. If the movement is only slight such as might be effected by accidentally touching the outer end of the wringer, the spring 55, acting through the bell cranks 58 and 58a, immediately returns the wringer to the center position. The restoring force of the spring 55 increases with increasing displacement of the wringer from the center position. Upon a somewhat greater pivotal movement of the wringer frame the arms 59, 59a of the bell crank levers are moved upward against a tab 62 on the latch lever 51 and start the movement of the latch lever to retract the latch pin 50 out of engagement with the latch surface 53 (or 54). The slight lost motion between the arms 59, 59a and the tab 62 prevents the starting of the latch release movement until there is more than a slight turning of the wringer frame about its pivots 11, 12. If the movement of the latch pin 50 is insufficient to move it clear of the latch surface 53 (or 54) the spring 55 returns the wringer to the center position as soon as the displacing force is removed. The force exerted on the latch pin 50 will normally move

it toward the bottom of the surface 53 (or 54) but this is not necessary and in any event is independent of the centering of the wringer by the spring 55. When the turning of the wringer is sufficient to move the latch pin 50 clear of the surface 53 (or 54), the control shaft 41 is released permitting the clutch to be returned to neutral in part by the torque reaction between the tapered driving teeth 38 and in part by a spring force transmitted from a spring 63 surrounding an index lock pin 64 through a plate 65 to surfaces 66, 66a on the latch plate 42. The lower end of the plate 65 has an inwardly extending flange 67 guided on a reduced upper end 68 of the index lock pin 64. The upper end of the plate 65 extends in back of the latch plate 42 and has at each side an outwardly extending tab 69, 69a for cooperation with the surfaces 66, 66a on the latch plate. The construction described so far provides a sensitive release for the roll drive which may be actuated by the instinctive or reflex pull of the operator to escape from the rolls. Once the drive to the rolls has been interrupted the panic condition is removed. The interruption of the roll drive accordingly serves as a safety release.

The pivoting of the wringer frame substantially on an axis passing through the roll drive end of the coupling 14 permits a more sensitive release without obtaining unwanted releases. If the axis of the pivots 11, 12 is shifted to the opposite end of the coupling 14, the driving force exerted by the coupling on the roll drive shaft 16 causes the wringer frame to oscillate at roll shaft speed about its pivots and under extreme loads the oscillation may cause tripping of the release. Even if the oscillation of the wringer frame is insufficient in itself to trip the release, the oscillation is objectionable. The oscillation introduces a variable in the force required to trip the release which prevents the use of a sensitive release if unwanted releases are to be avoided. There is also psychological objection to the oscillation or wabbling of the wringer frame during use.

The wringer drive gearing may be set and released from the driving position by the control handle 47. In the neutral position of the gearing, the latch pin rests in a rounded depression 70 in the cam plate 44 which centers the control handle in the neutral position. In this position, the latch plate 42 is centered by engagement of the surfaces 66, 66a with the tabs 69, 69a on the plate 65. The initial movement of the handle 47 takes up the lost motion in the pin and slot connection 43 and brings one of the rounded cam projections 71 under the latch pin 50. This raises the latch pin to the level of surfaces 72 on the latch plate. Upon further turning of the handle, the cam and latch plate move together until the latch pin 50 snaps behind the surface 53 or 54 holding the clutch in the engaged position. When the pin 50 engages the surface 53, the surface 66a on the latch plate engages the tab 69a on the plate 65 forcing the plate downward against the spring 63. When the pin 50 engages the surface 54, the surface 66a is clear of the tab 69a and the surface 66 engages the tab 69 to force the plate 65 downward. In either case, the latch plate is urged toward neutral by the spring 63. Only a short travel of the handle is necessary because of the large diameter of the eccentric 37. In the engaged position of the clutch, there is sufficient lost motion in the pin and slot connection 43 so that upon movement of the handle 47 back to

ward neutral, one of the rounded projections 71 on the cam plate lifts the latch pin clear of the latch surface 53 or 54 before the lost motion is taken up. Thereafter, the release of the roll drive takes place under the force of the spring 63 and the torque reaction between the tapered teeth 38. If the spring and torque action is insufficient to release the drive, the drive may be forcibly released by turning the handle back to neutral

At the lower end of the wringer head is a depending tubular sleeve 73 telescoped over the upper end of the wringer post 32. In the inner surface of the sleeve are grease grooves 74 which help in preventing binding on the wringer post. The lower end of the sleeve 73 has an arm 75 in line with the wringer frame carrying a dome-shaped hardened projection 76 which cooperates with chamfered holes 77 in an index collar 78 on the wringer post to locate the wringer in the desired angular position. Diametrically opposite the arm 75 is an arm 79 slidably carrying in its outer end a U-shaped hold down plate 80, the lower arm 81 of which is hooked beneath the index collar 78 and the upper arm 81a of which engages a spring 82 around the index lock pin 64. The spring 82 reacts between a seat 83 and the arm 81a and partially counter-balances the overhung weight of the wringer frame.

The wringer is yieldably indexed by the interfitting of the projection 76 in the chamfered index holes 77, the resistance being determined by the angle of chamfer. Rounding the projection 76 does not change the initial resistance but makes subsequent turning smoother than as if the projection 76 had a conical surface matching the chamfer. Turning of the wringer head relative to the index collar 78 results in lifting of the wringer. It is therefore desirable that the wringer slide freely and not bind on the wringer post so the projection 76 will drop in the desired index hole. The grease grooves 74 and the counterbalance spring 82 prevent binding on the wringer post.

An interlock between the index and the roll drive is desirable so the wringer will always be locked in index position when the rolls are being driven. This interlock is provided by the index lock pin 64 which registers with one of the holes 77 in each index position. The index lock pin is guided in a projection 84 on the cover plate 40 and in hole 85 and in hole 86 in the arm 79. In the driving position, the plate 65 engages shoulder 87 on the index lock pin and forces it down well through the registering opening 77. There is a substantial clearance between the opening 77 and the index lock pin so the index lock pin merely serves as a safety stop or lock holding the wringer indexed under stall loads as explained in greater detail in my application Serial No. 671,593. This results in a wringer which is yieldably held in any selected index position in the absence of other forces, the yieldable restraint being insufficient to prevent movement of the wringer to another position by a push on the wringer if the index lock pin is disengaged. The clearance between the index lock pin and the registering holes 77 prevents binding. The hold down plate 80 has a limited travel permitted by a slot 88 through which an attaching screw 89 extends so it is impossible to put the wringer in driving condition unless the index lock pin registers with one of the holes 77. The hold down plate 80 will not permit the necessary lifting of the wringer head. The hold down plate is guided between walls 90 on the arm 79. A plate 91 between the

head of the screw 89 and the plate 80 prevents loosening of the screw.

When the safety release is operated, for example, by pulling the wringer, there is a substantial tendency for this pull to also move the wringer out of its index position due to the retraction of the index lock pin by a spring 92. Thus an operator merely intending to stop the wringer drive by pulling on the clothes finds the wringer moved out of position. This nuisance tends to discourage the use of the safety release for stopping and thereby renders the use of the safety release less likely under panic conditions.

This is prevented by a blocking plate 93 slidably carried on the cover plate 40 in back of the bell cranks 58, 58a, the latch plate 42 and the plate 65. When the wringer is standing in neutral position, the upper end of the index lock pin 64 engages a tab 94 and forces the upper end 95 of the blocking plate 93 between the walls 61, 61a of the frame bracket 8. This blocks the pivoted articulation between the wringer and head and makes the indexing smoother in that the only additional movement is the slight up and down movement of the wringer head as the wringer is turned from one index position to another. In the driving position, the blocking plate 93 falls by gravity. If it should stick, the spring 92 engages a tab 96 and forces the blocking plate down. This moves the upper end 95 of the blocking plate clear of the bracket so the safety release is conditioned for operation. Upon operation of the safety release, by pushing or pulling the wringer, the bracket 8 moves over the top of the blocking plate (Fig. 10) holding the index locking pin down and thereby preventing movement of the wringer from the index position. Upon letting go of the wringer, the spring 55 returns the wringer frame to the central position permitting the lifting of the index pin and blocking plate.

In use, the wringer drive is set for the desired direction of rotation by the control handle 47. This is only possible when the wringer is in one of the index positions. Setting the drive latches the clutch 33 in driving position, depresses the index lock pin 64, and lowers the blocking plate 93 freeing the articulation between the wringer frame and head. The wringer may be stopped by the control handle but it will be found more convenient to exert a slight tug on the clothes going through the rolls. This pivots the wringer frame relative to the head and lifts the latch pin 50 to release the roll drive clutch. The clutch is returned to neutral by the force of the spring 55, 63 and the torque reaction between the tapered teeth 38. The torque compensation prevents or minimizes variation of the releasing force with load. The release of the roll by a tug on the clothes going through the rolls does not release the index lock pin 64. This is prevented by the blocking plate 93 until after the wringer has been returned to its central position by the spring 55. If the operator wishes to move the wringer to another index position, the more convenient procedure is to first stop the wringer by a push or pull on the wringer frame then allow the wringer to return to its central position so the blocking plate is lifted and then move the wringer to the new index position.

There is substantial independence in the design of the various functions of the wringer. The sensitivity of the safety release is determined almost solely by the strength of the centering spring 55. This spring exerts a restoring force proportioned to the displacement of the wringer

from its center position. The magnitude of the spring force can be kept just above the nuisance level, the level at which accidental touching of the wringer causes unwanted operation of the safety release. The force required to index the wringer is determined by the angle of chamfer on the index holes 77, the weight of the wringer, and the force of the counterbalance spring 32. This force can be kept to a negligible value since the index is never operated until after operation of the safety release. The blocking of the index lock until after the wringer has been centered makes it unnecessary to have a differential between the index force and the safety release force so as to prevent unwanted operation of the index upon operation of the safety release. The force required to set the gears in driving position is determined by the spring 63 which has a stiffness so related to the angle of the driving teeth 38 that the gearing is always returned to neutral, even under stall conditions.

What I claim as new is:

1. In a swinging wringer having a head, a frame articulated to the head, a detent yieldably indexing the head in any one of a plurality of angular positions, a roll reversing drive of the type latched in the driving position and biased to neutral, and a release for the roll drive latch, actuated by articulation of the frame from a center position, the combination of an index lock positively restraining movement of the head from an index position and having a lost motion connection with the drive such that the index lock can remain in the locked position while the drive moves from the driving position, means setting the index lock in the locking position with the setting of the drive in the driving position and releasing the index lock in the neutral position of the drive, means biasing the index lock from the locking position, and means blocking unlocking of the index lock upon articulation of the frame from its center position but not in its center position.

2. In a wringer, a head having drive mechanism including a roll drive shaft, means yieldably indexing the head in any one of a plurality of angular positions, and an index lock restraining yielding movement of the head from an index position beyond a predetermined range, a roll carrying frame, an angularly tiltable coupling having one end engaging the shaft and the other for engagement with said roll, means mounting the frame on the head for movement on an axis intersecting the roll end of the coupling, means blocking unlocking of the index lock upon movement of the frame relative to the head, and a safety release releasing said drive mechanism and actuated by movement of the frame relative to the head.

3. In a swinging wringer having a head, having a roll drive shaft, a roll carrying frame articulated to the head, a coupling having one end engaging the shaft and the other end for engagement with said roll, a detent yieldably indexing the head in any one of a plurality of angular positions, a roll drive of the type latched in the driving position, a release for the roll drive latch, actuated by articulation of the frame from a center position, an index lock positively restraining movement of the head from an index position, means setting the index lock in the locking position with the setting of the drive in the driving position, means biasing the index lock from the locking position, and means block-

ing unlocking of the index lock upon articulation of the frame from the center position.

4. In a swinging wringer having a head, a frame articulated to the head, index means holding the head in any one of a plurality of angular positions, a safety release latch member biased to the latch position, bell cranks each having one arm engaging yieldably and centering the frame and the other arms interconnected to move together, a connection between one of said first mentioned arms and the latch member effective to move the latch member toward the release position, an index lock restraining movement of the head from an index position and biased to unlocked position upon actuation of the safety release and a block effective to prevent unlocking of the index lock upon articulation of the frame from the center position.

5. In a swinging wringer having a head with roll drive gearing, a roll carrying frame articulated to the head for movement relative to the head under a thrust in the direction to swing the wringer, cam faced detents yieldably indexing the head in any one of a plurality of angular positions, said detents exerting a restraining force sufficient to hold the head indexed but insufficient to prevent movement to another position by a push on the wringer, means resiliently centering the frame on the head, a safety release including means for releasing the drive gearing actuated by articulation of the frame, an index lock for positively restraining the head in the selected index position, means biasing the lock to the unlocked position, spring means releasing the index lock upon actuation of the release, and a block preventing unlocking of the index lock upon articulation of the frame from its centered position.

6. In a swinging wringer having a head including drive mechanism, a wringer post having an index collar on which the head swings, an index pin in the head, means biasing the pin upward away from the collar, an interlock member for forcing the pin downward, said member being slidable upward on the pin, means biasing the member upward, a connection between the member and the drive mechanism moving the drive mechanism off by upward movement of the member, a latch holding the drive on, and a safety release for releasing the latch.

7. In a swinging wringer having a head including drive mechanism, a wringer post having an index collar on which the head swings, said collar having index holes, a cam faced projection on the head engageable with the holes and yieldably centering the wringer in an index position, an index pin in the head of substantially less diameter than the index holes, means biasing the pin upward away from the index hole, an interlock member for forcing the pin downward, said member being slidable upward on the pin, means biasing the member upward, a connection between the member and the drive mechanism moving the drive mechanism off by upward movement of the member, a latch holding the drive on, and a safety release for releasing the latch.

8. In a swinging wringer having a wringer frame and head, means yieldably indexing the wringer head on a support in any selected one of a plurality of index positions, said means offering sufficient restraint to hold the wringer in the selected index position in the absence of other forces but insufficient to prevent movement to another index position by a push on the wringer,

means mounting the wringer frame for bodily movement relative to the head and centering the frame on the head, a safety release including an operative connection actuated by bodily movement of the wringer frame relative to the head from its centered position, a positive index lock for positively restraining movement of the wringer head from the index position, means biasing the index lock to the unlocked position, reversing drive gearing in the head, interlock means between the drive gearing and the positive lock including a lost motion connection compelling movement of the positive lock to the locking position upon setting of the gearing in the driving position but not compelling unlocking movement of the positive lock upon setting of the gearing in the off position, and means blocking unlocking of the index lock upon bodily movement of the wringer frame relative to the head from its centered position on the head but not in its centered position.

9. In a swinging wringer having a wringer frame and head, means yieldably indexing the wringer head on a support in any selected one of a plurality of index positions, said means exerting a force restraining swinging of the wringer head from the selected index position sufficient to hold the wringer in the indexed position but insufficient to prevent movement to another index position by a push on the wringer, means mounting the wringer frame for bodily movement relative to the head and centering the frame on the head, a safety release including an operative connection actuated by bodily movement of the wringer frame relative to the head from its centered position, a positive index lock for positively restraining movement of the wringer head from the index position, drive gearing in the head, a control for setting the gearing in driving and neutral positions, means biasing the positive lock to the unlocked position, an interlock between the control and the positive lock setting the positive lock in the locking position with the setting of the gearing in the driving position and unlocking the positive lock with the setting of the gearing in the neutral position, a lost motion connection between the control and the positive lock permitting the positive lock to remain in the locking position until the gearing is moved from the driving position, and means blocking unlocking of the index lock upon bodily movement of the wringer frame relative to the head from its centered position on the head.

10. In a swinging wringer having a wringer frame and head, means yieldably indexing the wringer head on a support in any selected one of a plurality of index positions, said means exerting a force restraining swinging of the wringer head from the selected index position sufficient to hold the wringer in the indexed position but insufficient to prevent movement to another index position by a push on the wringer, means mounting the wringer frame for bodily movement relative to the head and centering the frame on the head, a positive index lock supplementing the yielding index and positively preventing movement of the head from the index position, drive gearing in the head, interlock means between the drive gearing and the positive lock of the type compelling setting of the lock in the locking position upon setting of the drive gearing in the driving position but not compelling unlocking movement of the positive lock upon setting of the drive gearing in the off position, means bias-

ing the positive lock to the unlocked position, a safety release including an operative connection between the frame and said drive gearing for returning the drive gearing to the off position and actuated by bodily movement of the wringer frame relative to the head, and means blocking unlocking of the index lock upon bodily movement of the wringer frame relative to the head from its centered position on the head.

10 11. In a swinging wringer having a head and frame, means yieldably centering the wringer head in any selected one of a plurality of angular index positions, said means yieldably exerting a force restraining swinging of the wringer head from the selected index position less than that required to hold the wringer indexed under stall loads, a safety release actuated by a thrust on the wringer frame in the direction to swing the same, an index lock for positively restraining swinging of the wringer head from an index position, said index lock having lost motion taken up by swinging of the wringer head from the centered position, means biasing the index lock to the unlocked position, means blocking unlocking of the index lock upon setting of the release, and means responsive to a thrust on the wringer frame in the direction to swing the same for blocking unlocking of the index lock.

12. In a swinging wringer having a head, a roll carrying frame articulated to the head, means yieldably indexing the head in any one of a plurality of angular positions, said means yieldably exerting a force restraining swinging of the head from an index position less than that required to hold the head indexed under stall loads, a safety release actuated by articulation of the frame, an index lock for positively restraining swinging of the head from an index position, said index lock having lost motion taken up by swinging of the head from an index position, means biasing the index lock to the unlocked position, and a block effective to prevent unlocking of the index lock upon articulation of the frame.

13. In a swinging wringer having a head and a frame, means yieldably indexing the wringer head in any one of a plurality of angular positions, said means exerting a force restraining swinging of the wringer head from an index position less than that required to hold the wringer indexed under stall loads, means mounting the wringer frame for bodily movement under the instinctive reaction of the operator, a safety release actuated by said bodily movement of the wringer frame, an index lock for positively restraining swinging of the wringer head from an index position, said index lock having lost motion taken up by swinging of the wringer head from the index position, and means biasing the index lock to the unlocked position.

14. In a swinging wringer, a drive head having clutch members, index means centering and yieldably holding the wringer head in any selected one of a plurality of angular positions with a force insufficient to prevent deliberate repositioning by pushing the wringer against the holding force of the yieldable index means, a positive index lock having in the locking position surfaces disengaged throughout and offering no restraint in the centered position of the wringer and interengageable upon, and positively limiting, movement of the wringer from the selected index position, spring means biasing the lock to the unlocked position, a control for the drive clutch members, an operative connection between the control and the lock moving the lock to the lock-

11

ing position as the clutch members are engaged and unblocking movement of the lock to the unlocked position as the clutch members are disengaged, a roll-containing wringer frame articulated to the head, means yieldably centering the frame on the head whereby the frame may be articulated from the centered position by a force such as the instinctive reaction of the operator to escape from the wringer rolls, a safety release actuated by articulation of the wringer frame from the centered position, and blocking means for preventing movement of the index lock from the locking position, said blocking means being ineffective in the centered position of the wringer frame and effective upon articulation of the wringer frame from the centered position.
